UNITED STATES PATENT OFFICE.

THOMAS B. LUPO, OF NEW YORK, N. Y.

COLUMN FOR INTERIOR DECORATION.

No. 882,398.

Specification of Letters Patent. Patented March 17, 1908.

Application filed January 31, 1907. Serial No. 355,127.

To all whom it may concern:

Be it known that I, THOMAS B. LUPO, citizen of the United States, residing at New York, in the county of New York and State 5 of New York, have invented new and useful Improvements in Columns for Interior Decoration, of which the following is a specification.

This invention relates to columns for interior wood-work, more particularly to those 10 which are made up of several materials so as to economize in cost and in weight, as will be more fully described in the following specification, set forth in the claims and illustrated in the accompanying drawings.

Figure 1 is an elevation of a column constructed in accordance with this invention. Fig. 2 is a view showing the various parts in section.

20 In the use of wood in the construction of solid columns the same is open to numerous objections, particularly the cost, the weight and the liability of the wood to crack in consequence of the dry atmosphere of the interior of buildings and in order to overcome these objections various attempts have been made to construct columns of materials 25 which are not liable to warp and at the same time are of light weight.

30 The object of this invention is to build up a column of materials which are not only easy to construct but which are cheap and which may be cut into the required length, which shall be fireproof and at the same time 35 possess considerable strength and able to support the weight put upon them.

The column shown in the drawings is made up of several rolls or layers of paper, asbestos, or similar flexible material, the 40 interior layer 3 being wound in a different direction from the outer layer 4 and pasted beneath the same. This method of making paper rolls is commonly used and the roll 45 consists of strips of paper wound spirally from end to end, the ends forming a close joint and the reinforcing strip is similarly

wound upon the first strip and pasted thereon, making a tube which is able to stand considerable longitudinal pressure.

Upon the exterior of a tube thus constructed I attach a veneering of wood 5 secured in any desired way but preferably by waterproof glue. This veneer may be polished and varnished and given the appearance of a solid column of wood of any desired kind. The top of such a column is provided with a cap 6 having extending flanges 7 to cover the upper edge of the column, and to this cap may be secured any suitable ornamental top or head. The lower end of the 60 column is provided with a base 8 having an annular groove 9 to receive the lower end of the column and in which a certain amount of glue may be put to firmly secure the column therein. This base 8 may be suitably ornamented and may be used as a means for securing the column to a floor. The paper roll forming the foundation for this column may be of fireproof material or have reinforcing means of metal or fabric and various other 65 modifications may be resorted to without departing from the essential features above described.

What I claim as new and desire to secure by Letters Patent is:

The herein described column comprising a hollow tube made up of strips of flexible material wound spirally, one layer upon another, and each alternate layer being spirally wound in the direction opposite to the next 80 adjacent layer, a wood veneer covering for said column, a cap having a projecting portion fitted within the top of the column, and a base having an annular groove to receive the lower end of the column, substantially as 85 described.

In testimony whereof, I affix my signature in presence of two witnesses.

THOMAS B. LUPO.
